CLAIM

The ornamental design for a lever for portable wrench support, as shown and described.

DESCRIPTION

FIG. 1 is a side elevational view of a lever for portable wrench support showing my new design in slidable disposition on a stand, it being understood that the broken lines representing a stand are for illustrative purposes only and form no part of the design;

FIG. 2 is an enlarged side elevational view thereof;

FIG. 3 is an enlarged rear elevational view thereof;

FIG. 4 is an enlarged top plan view thereof; and

FIG. 5 is an enlarged front elevational view thereof.
